Specification for Design.

Patented Sept. 1, 1914.

Application filed June 27, 1914. Serial No. 847,764. Term of patent 7 years.

To all whom it may concern:

Be it known that I, ROBERT CASARETTO, a subject of the King of Prussia, and a resident of the city of Crefeld, Germany, and whose post-office address is 7 Alexanderplatz, have invented a new and original and ornamental Design for Textile Fabrics, of which the following is a specification, reference being had to the accompanying drawing, forming part thereof.

The figure is a plan view of a portion of the textile fabric, showing my new design.

I claim:

The ornamental design for a textile fabric, as shown.

Signed at the city of Aix-la-Chapelle, Germany, this 9th day of June, 1914.

ROBERT CASARETTO.
